UNITED STATES PATENT OFFICE.

WILLIAM D. FORSYTH, OF YOUNGSTOWN, OHIO, ASSIGNOR TO RAILWAY PRODUCTS CORPORATION, OF BUFFALO, NEW YORK, A CORPORATION OF NEW YORK.

CAR PART.

1,125,293.

Specification of Letters Patent.

Patented Jan. 19, 1915.

Application filed December 4, 1913. Serial No. 804,676.

To all whom it may concern:

Be it known that I, WILLIAM D. FORSYTH, a citizen of the United States, and a resident of Youngstown, in the county of Mahoning 5 and State of Ohio, have invented new and useful Improvements in Car Parts, of which the following is a specification.

My invention relates to the parts of railway cars, such as bolsters, truck side frames, 10 brake beams, and the like.

The principal objects of my invention is to provide a truss member for a car part which constitutes the compression and tension members of a king-post truss and which can 15 be cheaply and easily made from a single plate of metal.

A further object of my invention is to provide a truss member of the character specified which will be strong and yet light, 20 and which will be slightly resilient.

Further objects of my invention are to attain certain advantages as will be more fully set forth hereinafter.

The invention consists in a truss member 25 for a car part in which the portions thereof are integral and are made from a single plate of metal, and which constitutes the tension and compression members of a king-post truss.

30 In the accompanying drawing, which forms part of this specification, and in which like reference characters refer to like parts throughout the several views, Figure 1 is an end elevation of the blank from 35 which a car part embodying my invention is made, said blank being in the form of a slotted metal plate; Fig. 2 is a plan view of the blank shown in Fig. 1, showing the slits therein; Fig. 3 is a cross-section on the line 40 $a-a$ on Fig. 4; Fig. 4 is a plan view of the blank after flanges have been formed along its edges and certain parts have been displaced from its plane; Fig. 5 is a side elevation of the blank after the middle portion 45 thereof between the slits has been stretched and displaced from the remaining portions of the blank; Fig. 6 is an end elevation of the blank after its side portions have been bent up to form the finished truss member; and Fig. 7 is a side elevation of the finished 50 truss member.

In making the car truck side frame shown in the accompanying drawing, the blank 1 is formed by cutting off the corners of an 55 oblong metal plate along straight or curved

lines 2, as shown in Fig. 2. After the corners of the blank 1 are cut off, spaced slits 3 are made in said blank. These slits 3 extend longitudinally of the blank 1 and terminate short of its ends. These slits 3 are shown 60 as having their middle portions parallel and their end portions converging; but they may be curved or otherwise shaped according to the proportions of the finished car part desired. The intermediate portion of the 65 blank 1 is divided by the slits 3 into three longitudinal portions consisting of two side portions 4 and a middle portion 5. The side portions 4 and the middle portion 5 are integral with the end portions 6 of the blank 1. 70

The longitudinal edge portions of the blank 1 are bent along lines parallel to its longitudinal edges to form flanges 7 projecting from said blank in the same direction. The flanges 7 may be formed before 75 the blank 1 is slotted, in order that the flanging operation will not spread the slits. The longitudinal edge portions of the middle portion 5 are bent along parallel lines 8 passing through the ends of the slits 3 to 80 form flanges 9 which project from the blank 1 in a direction opposite to the direction in which the flanges 7 project. The middle portion 5 of the blank 1, together with its flanges 9, is stretched and displaced from 85 the plane of the end portions 6 in a direction perpendicular to the plane of said blank, as shown in Fig. 5, that is, perpendicular to its own plane. The middle portion 5 of the blank 1, after it has been stretched 90 and displaced, as described, has a middle straight portion 11 which is in a plane substantially parallel to the plane of the end portions 6 of the blank 1, and two straight portions 10 and 12 which incline upwardly 95 from the ends of said middle straight portion 11 to the end portions 6. The middle portion 5 of blank 1 is of uniform width, and the flanges 9 thereon are widest through- 100 out its middle region.

After the middle portion 5 of the blank 1 has been displaced, as described, (Fig. 5), the side portions 4 with the flanges 7 thereon are bent along parallel lines 13 which extend longitudinally of the blank 1, so that 105 the flanges 7 project toward each other, as shown in Figs. 6 and 7. These operations described give the truss member its finished form in which there is an opening 14. In the opening 14 is fixed a tie or strut member, 110

not shown, to make a complete king-post truss. The truss member, hereinbefore described, constitutes the tension and compression members of a king-post truss adapted for a car part and is made from a single plate by cutting and bending or pressing operations which may be performed by suitable presses, dies or other apparatus. The different operations may be performed 10 while the metal plate is hot or cold. The metal where the compression and tension members of the truss member join is in substantially the same condition as it was in the original plate, and the compression and tension members are therefore more 15 strongly joined than if they were made from separate pieces of a corresponding size riveted or otherwise fastened together. The shape of the original plate, the shape of the 20 slits and the lines of bending may be varied so that the metal of the original plate can be distributed throughout the finished 25 truss member. The particular truss member shown is designed for a car truck side frame, and the blank is so shaped, slotted and bent that the metal is distributed and bent throughout the side frame according to the stresses existing therein. The compression and tension members are stiffened by the 30 flanges 7 and the flanges 9 respectively. In the construction shown and described, each flange 9 of the tension member lies in the same plane with one of the side portions 4. The advantage of this last-mentioned construction is that the car part is symmetrical 35 about a vertical median longitudinal plane, and the stresses are better distributed in it.

While for the purpose of illustration, the invention is shown as embodied in a struc-

ture which is particularly adapted for use 40 as a car part, it may be used for other purposes.

The particular construction shown and described can be considerably varied without departing from my invention, and I do 45 not wish, therefore, to be limited to the details of this particular construction.

What I claim as my invention is:

1. A car part made from a single piece of metal and comprising two spaced strips 50 having flanges thereon, and a flanged strip of uniform width arranged between said first-mentioned strips and integral with said first-mentioned strips for a portion of their lengths at their ends, said first-mentioned strips and said flanged strip having their respective middle portions spaced apart, said flanges of said flanged strip being widest throughout its middle region. 55

2. A car part made from a single piece of 60 metal and comprising two spaced strips and a flanged strip arranged between said first-mentioned strips and integral with said first-mentioned strips for a portion of their lengths at their ends, said first-mentioned strips and said flanged strip having their respective middle portions spread apart, each one of said first-mentioned strips lying in the same plane with one of the flanges of 65 said flanged strip.

In witness whereof I have hereunto subscribed my name in the presence of two subscribing witnesses.

WILLIAM D. FORSYTH.
